UNITED STATES PATENT OFFICE.

HALE E. HAWK, OF CRENSHAW, MISSISSIPPI.

PROCESS OF MILLING COTTON-SEED.

No. 825,534.

Specification of Letters Patent.

Patented July 10, 1906.

Application filed December 26, 1905. Serial No. 293,412.

To all whom it may concern:

Be it known that I, HALE E. HAWK, a citizen of the United States, residing at Crenshaw, in the county of Panola and State of Mississippi, have invented new and useful Improvements in Processes of Milling Cotton-Seed, of which the following is a specification.

This invention is a process of milling cotton-seed, having for its object to obtain separate and different qualities of oil and cake and to provide a system whereby the yield of the products will be increased.

In the present or usual method of milling it is the practice to hull the grain and to separate the meats from most of the hulls, part of the hulls being left in or returned to the meats and mixed with the same. This mixture is then taken to the rolls and the cookers and the oil afterward expressed. The object of putting part of the hulls in with the meats is to increase the yield or amount, by weight, of the cake. The extent to which this mixing or adulteration can be made is limited by law in most States. The meats with the hulls mixed therein constitute a single-quality product, the resulting oil and cake being of a single grade. This practice has the defect that the oil is of inferior quality—that is, inferior to what it would be if the meats alone were used. The presence of the hulls in the product from which the oil is expressed makes the oil dark. It also produces difficulties and losses in cooking and pressing. Thus it is well known in the art that pure or unmixed meats should be cooked with a higher pressure and temperature and for a shorter time in order to produce the greatest yield of oil, whereas when hulls are mixed with the meats lower pressure and temperature and more time are required, this variation of treatment being required in consequence of the presence of the hulls and fibrous matter in the meats. The present practice is to endeavor to strike an average with respect to pressure, temperature, and time in the cooking and pressing in order to make the treatment correspond to the material as nearly as possible. This is defective, and the maximum yield of oil and cake is not obtained. Furthermore, the cake is of low and uncertain grade owing to the presence of hulls therein, since the amount of hulls cannot be exactly regulated, because it depends somewhat upon the nature of the seed, the nature of the hulling and separating, and the skill of the operator.

By the process herein disclosed a reduc-

tion and separation is effective whereby stock of two grades is produced, the No. 1 or prime grade containing nothing but pure meats and the No. 2 or inferior grade containing mixed meats and hulls. Each of these grades receives separate treatment, according to its nature, so that the oil resulting from the No. 1 grade is the maximum in quantity and quality and of best color and is merchantable as such, together with the pure cake resulting therefrom, and the No. 2 stock produces oil and cake of inferior grade. If desired, the cake of both grades can afterward be ground and mixed to produce a commercial article of a certain quality.

The accompanying drawing is a diagrammatic view or flow-sheet of an embodiment of the system.

Referring specifically to the drawing, the seed after being cleaned, as usual, is put through the huller 1; which may conveniently be of the breast and cylinder type. From this it is received on an ordinary shaking-screen 2. This effects a coarse separation, the meats and finer matter which go through the screen being run through a grinding-machine 3, which has the function of an equalizer or sizer. The purpose of this is to size or equalize the meats coming from the shaker, inasmuch as the meats or particles thereof are of different sizes, and when the stock enters the shaker from the huller some of the meats are large and some small, and the shaker necessarily must have large perforations for all meats to pass through, and consequently considerable lint and pieces of hulls also pass through. For subsequent treatment in the centrifugal rolls it is desirable or necessary that the meats be reduced to a substantially uniform size, so that on the first reel a finer perforation of cloth can be used. The grinding-machine is thus essential to reduce the meats to substantial uniformity of size, whereas it has little effect on the lint and hull particles. From the sizer or grinder 3 the stock is taken to a centrifugal reel 4, by which a separation is effected, the heavier particles being delivered to a separating-conveyer 5 and the lighter parts or tailings passing off for other treatment, as hereinafter explained. The separating-conveyer 5 has slides so arranged therein as to cut out or drop the meats as they pass therethrough, discharging them to a conveyer 6 in clean condition as high-grade stock, being practically pure meats. These are taken to

the No. 1 grinding-rolls 7, from which they pass to the No. 1 cookers 8, and thence to the No. 1 presses 9, producing oil of high grade and prime quality of light yellow color and a resulting pure or prime quality of cake.

The tailings from the shaker-screen 2 pass to a huller 10, preferably of the disk type on account of the finer reduction needed, and the product is taken therefrom to a centrifugal reel 11, which separates and delivers to a separating or perforated conveyer 12, in which the pure meats are cut out and delivered to the No. 1 rolls as part of the prime stock and the tailings to a conveyer 13. The tailings from the reels 4 and 11 and from the separating-conveyers 5 and 12 are all delivered to another disk huller 14, the product from which is taken to a centrifugal reel 15, separating-conveyer 16, and plain conveyer 17. The pure meats cut out in the separating-conveyer 16 go as part of the prime stock to the No. 1 rolls, and the remainder of the product from the separating-conveyer 16 is delivered as No. 2 stock to the No. 2 grinding-rolls 22. This stock consists partly of meats and partly of ground hulls. From the grinding-rolls it passes to the No. 2 cookers 23 and presses 24, producing a No. 2 or inferior quality of oil. The tailings from the reel 15 are taken to a finishing-reel 18, whose separating-conveyer 19 cuts out part of the meats, which go as pure meats to the No. 1 stock, and the remainder goes to the plain conveyer 20 and thence to the No. 2 rolls as part of the inferior stock. The practically clear hulls, lint, and fiber tail off the reel 18 to the lint and fiber packer or press 21, in which the matter is packed into bales for shipment, as it is valuable as stock for paper-making.

As stated before, the stock which goes to the No. 1 rolls, cookers, and presses is high-grade and practically pure meat. It is cooked with the proper pressure and heat to preserve the highest color and purity to the oil and cake, thus making its commercial value the highest, the oil being run to the storage-tank and the cake delivered ready to be ground into the meal or shipped whole. The stock delivered to the No. 2 rolls, cookers, and presses is there given the kind of treatment with respect to heat and pressure that the nature of the stock demands, producing a No. 2 oil and cake, which are delivered separate from the prime products.

It will be seen that there is one grade at least—that is, the prime grade—of which the operator has complete control, the nature of the seed or other local conditions having no

effect on the quality. Any uncertainty or variation is confined to the product of No. 2 stock instead of to the whole product, as heretofore. It prevents over and under cooking of the best-quality product and as a result gives a greater total quantity of oil, part of which is of prime quality and better than the average.

Although illustrated in connection with a particular apparatus, the nature of the machines is immaterial, since other machines to produce the same result would do as well. Therefore the invention is not limited to the exact embodiment shown.

I claim—

1. A process of milling cotton-seed, consisting of hulling the seed, separating the oil-bearing part of the stock into two grades, one containing substantially pure meats and the other containing meats and some of the hulls, and extracting oil separately from the latter grade.

2. A process of milling cotton-seed, consisting in hulling the seed, separating the stock into three products, one consisting of substantially pure meats, another consisting of meats and part of the hulls, and the other consisting of hulls, and treating the second of the products mentioned separately for the extraction of oil therefrom.

3. A process of milling cotton-seed, consisting in, passing the stock through a series of reductions, separating the substantially pure meats after each reduction, to form a high-grade oil-bearing product, separating mixed meats and hulls after part of the reductions, to form an inferior-grade oil-bearing product, and treating said inferior grade separately for the extraction of oil therefrom.

4. A process of milling cotton-seed, consisting in hulling the seed, separating the hulls and unreduced stock from the meats, reducing said meats to a substantially uniform size, separating the same from any hulls therein, passing the said hulls and unreduced stock through another hulling device, separating the product into substantially pure meats, mixed meats and hulls, and hulls or tailings, and treating separately the mixed meats and hulls, for the extraction of oil therefrom.

In testimony whereof I have signed my name to this specification in the presence of two subscribing witnesses.
